UNITED STATES PATENT OFFICE.

EDWARD E. KLEINSCHMIDT, OF CHICAGO, ILLINOIS, ASSIGNOR, BY MESNE ASSIGNMENTS, TO MORKRUM-KLEINSCHMIDT CORPORATION, OF CHICAGO, ILLINOIS, A CORPORATION OF DELAWARE.

TELEGRAPH PRINTER.

Application filed June 21, 1920, Serial No. 390,593. Renewed October 26, 1925.

To all whom it may concern:

Be it known that I, EDWARD E. KLEINSCHMIDT, a citizen of the United States, residing in Chicago, in the county of Cook and 5 State of Illinois, have invented certain new and useful Improvements in Telegraph Printers, of which the following is a specification.

My invention more particularly relates 10 to a printer of the typewriter type for use in a telegraph system.

The object of my invention is the provision of novel features in a telegraph printer of the character indicated by which 15 the speed of the printing is increased and the general efficiency of the machine improved.

My invention will best be understood by reference to the accompanying drawings in 20 which I have illustrated one embodiment of my invention, and in which Fig. 1 is a sectional view taken for the most part on the lines 1—1 of Fig. 2 looking in the direction of the arrows, the upper portion of Fig. 1 25 being taken, in general, on the upper part of the line 1—1, while the lower portion thereof is taken on the lower part of line 1—1; Fig. 2 is a plan view taken on the line 2—2 of Fig. 1; Fig. 3 is a front elevation of 30 the printer with parts broken away; Fig. 4 is an enlarged rear elevation of a part of the printer; Fig. 5 is an enlarged front elevation of the selecting device; Fig. 6 is a side elevation of the operating bar and associated parts for controlling the operation of 35 the carriage return; Fig. 7 is detail side view of the universal bar actuated by the type bars and the connection to the ribbon shield and spacing contact; Figs. 8 and 9 are detail views illustrating parts of the paper carriage; Fig. 10 is a detail view illustrating 40 the shift-locking mechanism; Fig. 11 illustrates a construction by which the movement of the universal operating bar fails to move a cooperating pull bar. Fig. 12 is a detail view illustrating the parts actuating the contacts controlling the signal bell; Fig. 13 is 45 a diagram illustrating the circuit connections of the printer, and Fig. 14 is a sectional front elevation illustrating the arrangement by which the various type bars of variable 50 lengths are operated in the same manner by the same movement imparted to the various pull bars.

Like reference characters indicate like 55 parts throughout the drawings.

I have shown at A, Fig. 2, the frame of the machine. I will first described the selecting mechanism by which the various type bars of the printer are selected and actuated. Referring now to Fig. 1, 1 is one of the type bars, of which it will be understood there is a plurality, and which in the form here illustrated are similar in construction to those used in a typewriter of well-known 60 form. All of the type bars are pivoted at a common fulcrum 2, and in normal or inoperative positions, their outer extremities rest on a pad 3. The pivotal points of the type bars are arranged in the segment of a circle 65 in the usual manner, in order to bring the type on the free ends of all of the type bars to the same point on the ribbon when the type bars are operated, a common curved bar, in the form here illustrated, providing 70 the pivot on which the type bars are hung. A series of vertically disposed arms 4 are pivoted at a common fulcrum 5; the upper ends of the arms being provided with pins 4^a engaging in slots 5^a at the inner ends of 75 the type bars. To each of the arms 4 is pivoted, at 4^b, a pull bar 6 to which is connected a spring 7 tending to depress the pull bars and pull the same to the left, as viewed in Fig. 1. In order that the same longitudinal 80 movement of the various pull bars 6, which it is convenient and desirable to produce, may produce the same movement of the various type bars, the pivotal connections of the arms 5 at their lower ends are arranged 85 in the form of a segment reversely arranged 90 with respect to the segment on which the type bars are pivoted, as best shown in Fig. 14. The pull bars 6 are all arranged in the same horizontal plane, and are preferably 95 pivoted to the arms 4 at points considerably below the middle of the latter. By the described arrangement, the same amount of longitudinal movement of each of the pull bars produces the same movement of the 100 upper ends of the arms 4, and of the type bars to which they are connected. While I have described a segment to which the lower ends of the arms 4 are pivoted, it will, of course, be understood that the same result 105 would be produced by straight sections arranged more or less in the form of a segment. Each of the pull bars is provided

with a downwardly projecting lug 6^a, which normally rests on a roller 8 normally extending beneath and which is common to all of said lugs. The roller 8 is mounted in a rocking frame 9 and is actuated by a magnet or solenoid 10. Mounted on the frame 9 is a universal bar or bail 11 which, when the frame 9 is moved to the right, as indicated in Fig. 1, engages the lugs 6^a on any of the pull bars 6 which may be depressed.

Selecting bars 12, the same in number as the selecting magnets, and here shown as 5 in number, are mounted in standards 13 and 14 transversely of and underneath the outer ends of the pull bars 6, as best shown in Fig. 3. The five selecting bars have slots cut in their upper edges to correspond with the code used to operate the typewriter, that is to say, by moving different combinations of the selecting bars longitudinally, slots in the upper edges of all of the selecting bars are brought into alignment in various positions and directly underneath the various pull bars, so that one of the latter is permitted to drop therein. Underneath the selecting bars is mounted in the standards 13 and 14 a longitudinally movable carrier 15 in which carriage five pawls 16 normally depressed by springs 16^a are pivoted. Latches 17, one for each pawl, are also pivoted on carrier 15, the latter being provided with shoulders, as shown in Fig. 3, which engage the pawl in both its depressed and elevated positions, a spring 16^a tending to force the upper end of the latch beneath the pawl and hold the latter in its elevated position. Each pawl is provided with a bent finger 16^b, which, when the pawl is raised, engages a notch 12^a formed in the lower side of the corresponding selector bar 12.

Each of the selecting magnets 18 is provided with an armature 19 pivoted at 19^a (see Fig. 2). Each armature is normally held away from the magnet by a spring 19^b (see Fig. 1). A projecting arm 19^c on the armature engages underneath a corresponding pawl, as shown in Fig. 3, in order to raise the latter when the corresponding magnet is energized.

A core 20 is actuated by the solenoid 21 which is known as the sixth impulse magnet. When solenoid 21 is energized and its core raised, the latter engages one arm of a bell crank 22 (see Fig. 5) pivoted at 22^a, the other arm of which engages carrier 15 in order to move the latter to the right, as viewed in Fig. 5. The forward movement of carrier 15 also actuates those selector bars with which the corresponding pawls are in engagement. When carrier 15 is substantially at the limit of its movement, the lower ends of the latches 17 engage the upwardly extending posts 23, as best shown in Fig. 3, and the latches are thereby disengaged from the pawls. A spring 24 (see Figs. 2 and 3),

which is preferably slit longitudinally for a portion of its length to provide, in effect, a separate spring for each selector bar, is provided with a V-shaped projection 24^a which engages in slots 12^b and 12^c in the selector bars when the latter are in their normal positions or moved to their forward positions, respectively.

A plate 27 is held against the forward end of the selector bars 12 by a light spring 29. This plate is engaged by a second plate 30, preferably formed at its upper end with a bent part 30^a, which engages the plate 27 and is held against the same by a comparatively stiff spring 31. The plate 30 is provided with an adjustable screw 32 which is engaged and moved by carrier 15 against the action of the comparatively stiff spring 31, and the selector bars and the pawls which actuate the same are thus relieved of the comparatively heavy work of moving the restoring plate 30 to the right, as viewed in Fig. 1.

When the plate 27 is moved to the right by the selector bars 12, as viewed in Fig. 5, a latch 33 pivoted at 34 and having a detent 33^a which normally rests against the plate 27 is pulled in behind the plate by a spring 35, and retains the plate in its forwardly moved position. The opposite end of the latch 33 is provided with a piece of insulating material 36 which bears against two flat contact springs 37 and 38 carrying contacts 37^a and 38^a, respectively, which normally engage two stationary contacts 40^a and 39^a, carried by spring fingers 40 and 39, respectively, thereby opening the two sets of contacts, while the latch is in the normal position shown in Fig. 2, the springs 37 and 38 closing the two sets of contacts when the latch is in its retracted position. Closing the first set of contacts 38^a and 39^a completes a circuit through the operating solenoid or magnet 10, the energization of which attracts the core 10^a to which is connected the link or links 41 which are, in turn, pivoted to an arm 42 which rotates shaft 43 and moves the frame 9 with the bail 11, in the manner previously described, to move forwardly any pull bar 6, which may have been depressed by dropping into the slot formed in the upper edges of the selector bars. The closing of the second set of contacts 37^a and 40^a completes a pre-energizing circuit through the magnet 66, the energization of the magnet at this time, because of the fact that a resistance 66^a is included in the circuit, being insufficient to operate its armature, but sufficient to reduce the time for its operative energization, in the manner hereinafter described. As the type bar 1 nears the end of its upward stroke, an arm 44 attached to rocker frame 9, and carrying a bar 45 sliding on a guide screw 46, engages

by means of an upwardly projecting lug 45^a 130

the latch 33 (see Fig. 6). The movement of the latch 33 releases plate 27, and it, together with plate 30 acted upon by springs 29 and 31, restores the selector bars 12 and 5 the storage carriage 15 to their normal positions, shown in Fig. 5; at the same time, contact springs 37 and 38 have forced contacts 37^a and 38^a away from their opposing contact points 40^a and 39^a, thereby causing 10 the magnet 10 to be deenergized, and the various parts connected to its armature to be returned under the tension of a spring 9^a. It will be apparent, therefore, that the magnet 10 is energized during the time that 15 the plate 27 is locked in the position to which it has been moved, and the magnet remains energized until the mechanism actuated thereby which operates the printing mechanism has been operated, and the plates 27 and 30 thereby released and permitted to 20 restore the selector bars to their normal positions. While the parts actuated by the magnet 10 are operating, the magnet 21, which operates the carriage 15, has been de- 25 energized and the carriage 15 restored to its normal position by a spring 15^a (see Fig. 5). By permitting the storage carriage to return while the parts actuated by the operating magnet 10 are operating, the "overlap" and speed of the device are correspondingly increased.

Means for regulating the force of the blow struck by the type bar 1, and thereby the impression on the paper are provided and 30 are shown in Fig. 6. The arm 42, which is actuated by the link 41, instead of being rigidly fastened to the rocker shaft 43 which carries the frame 9, moves freely thereon, while it imparts its motion to said shaft 45 through the medium of a spring 49 and an adjustable arm 50 secured to the shaft 43. A dash pot 48, the piston or plunger 47 of which is connected to the outer end of the arm 42, is provided to prevent shock to the parts moved by the solenoid.

The described apparatus for bringing about the operation of the selector bars and a printing operation constitutes one of the important features of my invention, since 50 it gives a greater "overlap" and increases the speed of the printing operation. It will be apparent that as soon as the carriage 15 and the selector bars 12 have been returned to their normal positions, a new combination 55 may be set up by the selector magnets while the printing operation brought about by the previous combination is being carried out.

I will now describe the next operation 60 in order following the printing of a letter by the type bar 1, which is letter spacing. Referring to Fig. 7, a rocker shaft 51, pivoted in bearings 52 and 53 which are a part of the frame work, carries two upwardly extending arms 54 and 55 which carry a bail 65 or universal bar 56, pivoted at their up-

per ends, as at 57 and 58. An extension 56^a of the bail projects into a recess in the block 59 (see Fig. 1). This extension 56^a serves to restore the type bars 1 on their pivots 2. When a type bar 1 is operated and approaches the end of its upward stroke, a shoulder 1^a near the pivot 2, engages the projection 56^a on the universal bar 56, and pushes it back against the tension of a spring 60 which is attached at its upper end to a stationary part, and is fastened at its lower end to a pin 61 in the rocker shaft 51. From the upright 55 extends a flange 62 (see Fig. 7) carrying an insulated screw 63 which bears against a contact spring 64 and in its normal position holds it away from and out of contact with spring 65, but when bail 56 is pushed back, as described, the two springs 64 and 65 make contact and close a circuit through the spacer magnet 66, as indicated in Fig. 13. No resistance is included in this circuit at this time, and the magnet 66 is operatively energized.

Referring to Fig. 2, the magnet 66 has an armature 67 carrying a pawl 68, which engages teeth on a ratchet wheel 69. When the magnet 66 is energized and draws the pawl 68 from engagement with the teeth on ratchet wheel 69, the ratchet wheel is prevented from following by a retaining pawl 70, which is arranged, however, to release the ratchet to permit the return of the carriage, in a manner which will be hereinafter more fully described. The operation of the magnet 66 causes no movement of the ratchet wheel 69, but after the type bar 1 has printed its character on the paper and has returned toward its normal position far enough to open contacts 64, 65 again, thus de-energizing magnet 66, the pawl 68 engages a tooth in advance of the one which it last held and rotates the ratchet wheel 69 one tooth, a spring 71 furnishing the motive power, which has been stored up in it by the operation of magnet 66.

Referring now to Fig. 4, the ratchet wheel 69 is fastened to a shaft 72 which carries at its upper end a pinion 73 engaging a rack 74, and forming a sliding engagement therewith when moved up and down in the manner hereinafter described. The rack 74 is attached to the paper carriage and a movement of one tooth on the ratchet wheel 69 moves the paper carriage forward one letter space. Each letter bar 1, Fig. 1, when operated causes the paper carriage to be moved forward one space, as described. Spaces between words are made in like manner, the only difference being that the particular bar 1 used for word spacing carries no type at its upper end, and, therefore, does not print on the paper.

The shaft 72 is enclosed by a casing or housing 721. A coiled tension spring 76 surrounds the shaft 72 and is disposed be-

tween the shaft and the casing. One end of the spring is fastened to the casing 721 while the opposite end thereof, and here illustrated as the lower end, is secured to a 5 collar 722 which is adjustably secured to the shaft 72 as by a set-screw 723. By the described means, the tension of the spring 76 may readily be adjusted.

Associated with the spacing magnet 66 10 is the carriage return magnet 75. The simultaneous operation of these two magnets is necessary to release the carriage and allow it to return under the tension of a spring 76 (see Fig. 4). The selection of the "carriage return" is made by the selecting arrangement in the same manner as a letter is selected, and such selection has already been described. The pull bar 6^b (see Fig. 6) 15 which controls the carriage return has only a vertical motion and its function is solely to close a contact. The horizontal motion which is imparted to letter bars 6 by the bail 11 striking the projection 6^a (see Fig. 1) is eliminated in the case of the bar 6^b by 20 cutting a slot 11^a in the bail 11 opposite the bar. There are three bars which are thus operated, namely, the carriage return, line feed and the figure shift. Attached to the 25 bar 6^b is a piece of insulating material 78 bearing against a spring 79 and which in its 30 normal position holds a contact on said spring out of engagement with a contact on a spring 80, the contacts themselves not being shown in Fig. 3, but being indicated in 35 Fig. 13. When closed the contact springs 79, 80 close a circuit including the carriage return magnet 75 and the space magnet 66 which is connected in series therewith, (see 40 Fig. 13). Referring to Fig. 2, a shoe 81 on the pawl 68 strikes a fibre block 82 as the armature 67 is pulled back and throws the 45 end of the pawl clear of the teeth on the ratchet wheel 69, at the same time that the magnet 75 attracts its armature 83 and disengages the retaining pawl 70 which is secured on said armature, the armature being pivoted at 83^a. Attached to the armature 83 is an arm 84 carrying a block 85 of insulating material which, when the armature 50 is attracted, moves the spring 86 into contact with screw 87.

Referring to circuit diagram, Fig. 13, it will be seen that the magnets 66 and 75 are now locked up through a circuit including 55 contacts 86, 87 and 88, 89 independently of contacts 79, 80, which close for a moment only during the operation of magnet 10. This locking circuit is provided so that ample time will be given for the carriage to 60 return before releasing the magnets 66, 75, which is accomplished by a lug on the carriage striking a contact 88 and breaking its contact at 89, (shown only diagrammatically in Fig. 13). This takes place only as the carriage reaches the end of its return, the

contacts 88, 89 being held open in that position, but immediately the carriage makes one space, contacts 88, 89 are again closed. In addition to the control of the carriage return by closing contacts 79, 80, which is 70 accomplished by sending the proper selective impulses over the line, a local carriage return circuit is provided and is completed by a push button 90 (see Fig. 13) in the side of the printer frame, which may be pressed into contact with the point 91, thus closing the same circuit as do contacts 79, 80. 75

Referring to Fig. 2, a manually operated arm 92 pivoted at 92^a carries a wire 93 constituting a link connecting said arm to the armature 83 of the magnet 75, said arm being held in the position shown by a spring 94 which is attached to the lever 92 at one end and presses against the block 82 at the other end. When lever 92 is moved against the tension of spring 94, it carries with it the armature 67 and pawl 68 of magnet 66; also by means of the wire link 93, it moves armature 83 of magnet 75 and disengages retaining pawl 70. The ratchet wheel 69 is now 90 free and the carriage is permitted to return under the tension of spring 76 as already described. 95

Line feed.

The operations involved in selecting the line feed is similar to the selection of the carriage return and need not be described. A pair of contact points 95, 96 (diagrammatically shown in Fig. 13, but not otherwise illustrated) are brought together and a circuit is closed through line-feed magnet 97, when the carriage is returned to its normal position. Magnet 97 is provided with an armature 98 which carries an arm 99 passing through a guide 100, and is held in the elevated position shown in Fig. 1, by a spiral spring 101 surrounding the armature. When magnet 97 is energized, a roller 102 on the upper end of arm 99 engages and forces down a plate 103. Plate 103, seen endwise in Fig. 1, is a flat plate which extends the length of the carriage so that regardless of where the carriage may be along the line, the relation of roller 102 to the plate 103 is 100 the same. Plate 103 is attached to a rod 104 105 pivoted in a frame 105 at each end of the carriage, only one frame appearing in Fig. 1. On the end of the rod 104 is an arm 106 (see Fig. 9) carrying a pawl 107 which is normally held down against a stop-pin 109 by a spring 110. The stop-pin 109 serves to hold the pawl 107 clear of the teeth of the ratchet wheel 108, while in its normal position. When the magnet 97 is energized, the pawl 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

mentum of the platen carrying it too far. To retain the platen roller in its proper position and insure even spacing between lines, an arm 113 carries a roller 114 which centers 5 the ratchet wheel 108 between two teeth under the tension of a spring 115.

Carriage shift.

The carriage is supported on two bars 10 or rails which are shown in section in Fig. 1. The rear bar 74 of the carriage on which the rack described is found, rolls on two balls 117 (one at either end), which are seated in a race formed in a stationary rail 116. The bars are kept in position by a 15 guide rack 118 having teeth in mesh with pinion 119 on the shaft 72. The pinion 119 is half the diameter of pinion 73, therefore the guide rack 118 moves half as fast 20 as rack 74. Rack 74 is held down against its ball-bearings by a spring clamp 120 and a roller 121. Rack 74 is not only free to move longitudinally, but to rock slightly on the balls 117 and under the roller 121 due 25 to the rounded upper face of rack 74, this permits the front of the carriage to be raised and lowered, i. e., lifted about balls 117 as a pivot. At the front of the carriage 30 is a roller 122 (see Fig. 1) which engages lifting bar 123. A guard 124 (see Fig. 1) prevents the carriage leaving the rail. Lift- 35 ing bar 123 is carried by a pair of arms 125 (only one of which is shown in Fig. 1) attached to either end of a shaft 126. When 40 it is desired to shift the carriage from letters to figures, a magnet 127 (see Fig. 4) is energized through the closing of contact springs 128, 129 (see Fig. 13), which is brought about in a manner similar to the 45 selecting of the line feed or of the carriage return, and which operation will not therefore be described. When the armature 128' is pulled down, it first unhooks a safety latch which is provided as a guard against 50 accidental shifting of the carriage by the operator. Referring to Fig. 10, the upper end of the armature 128' is connected to a lever 129' by a pin 128a. The lever 129 rocks on pivot 130 from its normal position 55 in which an upper jaw 129b is held against shaft 126 by a spring 131 until a lower jaw 129c strikes the shaft 126. In this position the hook 129a is released from the bracket 132 on rail 116. Further movement 60 of the armature 128 results in rocking the two arms 125 to lift or shift the carriage which rests on lifting bar 123. Referring to Fig. 1, attached to the shaft 126 is an arm 133 normally resting against a screw 65 134 (shown in dotted lines). A rocker 135 pivoted on a pin 136 carries a plate 137, shown in dotted lines. When the carriage is moved into the shifted position, the bevelled face 133a of the lever arm 133 forces 70 the plate 137 down until it passes the plate,

when the latter drops in behind and retains the arm 133, thereby retaining the carriage in the shifted position after the magnet 127 has been deenergized. It will be noted in Fig. 10, that a pull on the solenoid armature 128', due to the free play between jaws 129b, 129c and shaft 126, first releases hook 129a from bracket 132. As soon, however, as lower jaw 129c engages shaft 126 from below, members 129' and 125 act as a unit 75 double-armed lever, rocking on shaft 126, and the pull on armature 128' results in the lifting of lifting bar 123 and the shifting of the carriage from lower-case to upper-case position. On the deenergization of 80 solenoid 127, and the return to normal of armature 128', latch 129a will reengage bracket 132, so as to again prevent accidental shifting of the carriage. A locking circuit is also preferably provided for the 85 magnet 127 comprising an adjustable screw 127a, and cooperating contacts 127b, 127c and as this locking circuit is closed and opened in the same manner as that already described in connection with the sixth impulse 90 magnet 21, Fig. 5, the same need not be more fully described.

When it is desired to return the carriage to lower-case position, a predetermined pull bar 138 (Fig. 1) is selected. This rocks the 95 arm 135 on shaft 136, disengages plate 137 from lever arm 133 and allows the carriage to return.

Means for manually releasing the carriage from figure shift is also provided, Fig. 100 2, and comprising a push button 139 which projects through a hole in the frame of the machine. It is connected by means of a rod 140 to a bell crank lever 141 pivoted at 142. A spring 143 holds the lever in 105 its normally retracted position. When the button is pressed, the lever 141 strikes a downwardly projecting piece 144 attached to the pull bar 138 and rotates the rocker arm 135 to release the carriage, as already 110 described.

Signal bell.

Referring to the circuit diagram, Fig. 13, a magnet 145 has an armature 146, which, 115 when the magnet is energized, strikes a gong 147. Normally a pair of contacts 148, 149 are closed forming a short circuit around the magnet 145 and affording a path of low resistance from the battery to the space 120 magnet 66 whenever the contacts 64, 65 are closed. When one of the type bars, such as the J letter bar, is operated, and the carriage is shifted, a combination of movements occurs (to be described later), which separates the contacts 148, 149, and thereby places magnet 145 in series with magnet 66 125 while contacts 64, 65 are closed. The result of this circuit change is to energize magnet 145 and strike a single blow on the gong 130

147, while the added resistance of magnet 145, in series with magnet 66, 71, is sufficient to prevent the latter from overcoming the tension of its armature spring 71, and therefore prevents spacing.

Referring to Figs. 2, 4 and 12, 150 is an extension of one of the pull bars, here shown as the letter J pull bar, hinged to a bell crank lever 151, which rocks on a stud 152. At its forward end is a longitudinally adjustable piece 153. Whenever the J pull bar is selected and actuated, the motion transmitted to bell crank lever 151 causes a downward movement of part 153 forming a cam. If the carriage is in the letters position, and therefore the letter J is to be printed, the cam 153 passes by a beveled block of insulating material 154, attached to contact spring 148, and does not disturb its contact with spring 149. If, however, it is desired to give some signal by ringing the bell 147, the carriage is first shifted and then the J pull bar selected. Attached to the arm 133 are the two contact springs 148, 149, insulated therefrom by a block 156. The part 155 is merely a guard to protect the spring 148 from injury. Now when the carriage is shifted, the arm 133 carrying the springs 148, 149 is moved into such relation to part 153 that when J pull bar is selected, it strikes the beveled block 154 and forces the contact spring 148 away from 149, and the bell is thereupon rung, in the manner already described in connection with circuit diagram Fig. 13. When this operation takes place, the cam 153 engages a horizontal projection 155^a of the member 155 and prevents operation of the J type bar.

40 Ribbon feed mechanism.

The operation of the ribbon feed is as follows: Referring to Figs. 1 and 2, the ribbon 161 is fed alternately from two spools 157 and 158, which are carried at the upper ends of vertical shafts 159 and 160. At the lower ends of these shafts are ratchet wheels 162 and 163. Opposite each ratchet wheel is a pair of pawls 164, 165, 166 and 167. Retaining pawls 165 and 167 may rotate through a small arc of a circle about their stationary pivot points 168 and 169. Operating pawls 164 and 166 have both a rotating motion, like pawls 165 and 167, and a longitudinal motion which is imparted to them by virtue of their being pivoted at 170 and 171 on radial arms fastened to the shaft 172. Shaft 172 has an oscillating motion imparted to it by magnet 10, through the shaft 43, arm 173 secured on said shaft, bar 174 pivoted thereto and to an arm 175 (see Fig. 1). Arm 175 is not firmly attached to shaft 172, but imparts its motion thereto through a spiral spring 176 and an arm 177 rigidly attached to the shaft (see

Fig. 2). This flexible transmission is for a purpose which will appear later. It will be observed that, while pawls 164 and 165 are in operating relation to ratchet wheel 157, pawls 166 and 167 are held out of engagement with ratchet wheel 158 by pins 178 and 179 in the transverse bar 180, and vice versa. Thus, while the ribbon is being wound up on spool 157 by the pawl 164, it is free to unwind from spool 158. When the ribbon becomes fully unwound from spool 158, the bar 180 is automatically moved toward the spool 158, so that a pair of pins 181, 182 push the pawls 164 and 165 out of engagement with ratchet wheel 162, and pins 178 and 179 allow pawls 165 and 167 to engage the teeth on ratchet wheel 163 and rotate the spool 158. This automatic reversal is brought about in the following manner. Referring to Fig. 1, in the hub 183 at the upper end of the shaft 159 is a slot for the reception of a thin flat lever 184 which is pivoted on a pin 185. A spring 186 holds the lever in the position shown when the ribbon is unwound, but when the ribbon is wound on the spool 157, it forces the upwardly projecting part 184^a inwardly, so that the arm 184 lies close to the shaft above and below its pivot. In the path of arm 184 is an arm 187 attached to a vertical shaft 188 which carries an arm 189 connected by a pin to a bar 190. The bar 190 carries a pin 197 which extends through a slot 191^a in a lever arm 191. Lever arm 191 has longitudinal motion imparted to it by a radial arm 196 secured on the shaft 172, the connection being such, however, that lever arm 191 is not oscillated by the movement of the arm on which it is mounted. The arm 191 is bent down at the end, as at 191^b, and this downward projection engages one or the other of two lugs 195 or 196 on a lever arm 192. Arm 192 is pivoted on a stationary pin 194 and when the arm 191^a strikes a lug 195 or 196, it rocks the arm 192 and through a connecting pin 193 moves the bar 180 longitudinally for the purpose already described. In the foregoing description reference has been made to levers 184 and 187. It will be seen in Fig. 2 that similar levers on the other side of the machine are associated with the spool 158 and are adapted to impart motion to the bar 190 in the opposite direction from the parts associated with spool 157. The position of the various parts associated with the ribbon pad, as shown in the drawing, are illustrated in the positions which they occupy when the reversal of the ribbon feed has just been completed. The ribbon having unwound to the last turn release, the lever 184 which, under the tension of the spring 186, moves out into the path of the arm 187 which at this time occupies the position with relation to the spool hub, shown

at the top of Fig. 2, in connection with spool 158. When the last turn on the spool is unwound, the arm 184 forces the arm 187 into the position, shown at the bottom of 5 Fig. 2, with the result already described.

The function of the spring 176 is to permit of an independent adjustment of the ribbon-feed mechanism and the mechanism which operates the bail 11, any difference in 10 the adjustment of the two is taken up in the spring 176. It also serves to prevent excessive stress on the parts of the ribbon-feed mechanism, should any of its parts, or the ribbon itself become caught.

15 *Ribbon vertical movement.*

Referring to Fig. 1, it will be seen that the ribbon 161 in its normal position slopes downwardly from the spools and away from 20 the front of the platen, the purpose of which is to make the writing on the paper visible. Whenever a letter or character is to be written, the ribbon must be raised in advance of the approaching type bar 1, so that 25 it will be interposed between the paper and the character on the type bar. The universal bar 56 carried by the arms 54 and 55 is pushed back by the operation of type bars 1, in a manner already described in connection 30 with the spacing. The bar 56 has an upwardly extending arm 198 (see Fig. 1) provided with a slot 199 which serves as a guide for a pin 200^a in a rocker arm 200. The rocker arm 200 is pivoted on a pin 203 on an arm 201. When the slotted arm 198 is 35 pushed back by the engagement of the shoulder 1^a on a type bar 1 with the projection 56^a on the bail 56, the rocker 200 is rotated about the pin 203 and raises the arm 202 and 40 with it the ribbon, interposing the latter between the paper and the approaching type bar. When the carriage is shifted for the purpose of writing figures which are higher up on the type bars than letters, the ribbon 45 must be raised higher than for the letters. This is effected by actuating arm 201 secured on the shaft 126, which lifts the rocker 200 bodily and in the shifted position supports the rocker 200 on pin 203 at a 50 higher level.

Details relating to the carriage.

In Fig. 4 is shown a spiral spring 204 having one end attached to the frame 205 and 55 the other end to an arm 125' secured on the shaft 126. The function of this spring is to support a part of the weight of the carriage on the rail 123, Fig. 1, and make it easier for magnet 127 to shift the carriage. It also 60 reduces the violence of the blow as the carriage falls when released by the rocker 135.

Also in Fig. 4 is shown a dash pot, consisting of a cylinder 206, a piston 207 and a spring 208. This dash pot serves as a shock 65 absorber to reduce the force of the blow

which the carriage strikes when it returns to the beginning of a line. When the carriage is some distance from the beginning of a line, the piston 207 is in the position shown, but when it is released a lug 207^b on 70 the carriage strikes the projecting rod 207^a and drives the piston into the cylinder compressing the spring 208 and also the air confined in the cylinder and thus retards the speed of the returning carriage and prevents 75 shock.

Carriage construction.

A front view of the carriage is shown in Fig. 3 and certain enlarged details in Figs. 80 8 and 9.

Referring to Fig. 3, the platen roller 209 has a shaft 210 supported by bearings in the two end plates 105, 105'. At one end of the shaft is a knurled hard rubber knob 85 211 and at the other end a crank 212 for conveniently turning the roller. Parallel with the large roller 209 are several pairs of rollers arranged on either side of the platen 209, and here shown as three pairs 90 of such rollers 213, and 213' for holding the paper firmly and feeding it evenly, as the large roller is turned. The small rollers are held against the large roller by a spring 218 (see enlarged detail Fig 8). One end 95 of the spring 218 is fastened to a collar 216^a, to which the arm 216 is secured and which is free to rotate on shaft 220. The other end of spring 218 is attached to a collar 219 which is secured to shaft 220. Shaft 220 is 100 free in its bearings at either end. The spring 218, therefore, presses the rollers 213 and 213' against the platen equally.

Above the platen roller 209 is a metal strip 221 with a knife-edge at the rear against 105 which the paper may be torn off smoothly and evenly from time to time as the messages are fed up from the roller.

Referring to the enlarged detail Fig. 9, the metal strip 221 is held by an arm 222 110 at each end, which is pivoted on a rod 223. A spring 224 presses against the outer corner 222^a of the arm and holds the knife and attached clip down to the platen roller 209. A roller 225 (see Fig. 3) at each end rests 115 upon the platen and, when there is paper in the carriage, upon the paper and holds the strip 221 a short distance away from the roller 209. In putting paper into the carriage it is desirable to raise the strip 221 with its clips and rollers 225 up from the roller which may be done as the end pieces 222 may rotate the rod 223 back until the corner 222^a falls into the notch 224^a and retains it in that position.

Fig. 13 illustrates a diagram of the circuits including the circuits involved in selecting the various selector magnets. In the form here illustrated, a polarized relay 226 120 is included at one end of a line conductor 125

227. The polarized relay is provided with an armature 228 which engages a back contact or a front contact, depending upon whether the electric impulses sent over the line are negative or positive. The front contact for the armature is connected by a line conductor 229 to one terminal of each of the selector magnets 18, the other terminals of the magnets being connected to the respective contact segments 230 of a distributor 231. A sixth segment 232 is connected to the sixth impulse magnet 21. It will be understood that in the printing telegraph system, here shown as of the Baudot type, rotating distributors are provided at each of the stations and means are provided to cause the distributors to rotate in synchronism. The distributor is also provided with a collector or contact ring 233, connected by a conductor 234 to one terminal of the local battery 235, the contact ring 233 and the various segments 230 and 232 in the outer ring, and the inner ring 233 being bridged by a rotating brush 235^a. I have here illustrated a distributor which includes only a single channel, although it will be understood that my invention is equally applicable where a plurality of channels are employed. The other terminal of the battery 235 is connected by a conductor 236 to the armature 228 of the polarized relay. It will be understood that in operation, one or more of the selector magnets 18 are energized in various combinations for each character that is sent over the line.

Referring particularly to Figs. 5 and 13, the sixth impulse magnet 21 is energized, as stated, through a circuit controlled by the distributor 231. In order to maintain the magnet 21 energized a sufficient length of time to bring about the operation of the carriage 15, a locking circuit is provided therefor. Referring particularly to Fig. 5, a second armature 21^a, mounted on a spring finger 21^b, secured to a stationary part, as at 21^c, is provided with an adjusting screw 21^d which projects into the interior of the magnet 21 and into the path of movement of the core 20. Now, as soon as the magnet is energized by the circuit which includes the distributor, the armature 21^a is attracted and a contact 21^e carried by the spring finger 21^b engages a stationary contact 21^f and closes a locking circuit to the magnet 21, which includes the battery 235. As soon as the magnet 21 is fully energized and its armature 20 fully attracted, the core 20 engages the screw 21^d and lifts the spring finger 21^b and the contact 21^e from the contact 21^f to open the locking circuit, and permit the return of the carriage 15 by the spring 15^a.

Claims:

65 1. In a selecting mechanism; a plurality of selector magnets; a movable pawl carrier,

a plurality of pawls mounted on said pawl carrier and controlled by said selector magnets; and a plurality of movable selector bars controlled by said pawls; said pawls being in spaced relation in the direction of movement of said selector bars, with respect to each other.

2. In a selecting mechanism, a plurality of selector magnets; a movable pawl carrier; a plurality of pawls pivoted to said carrier and actuated by said magnets; a plurality of springs normally holding said pawls in un-actuated position, a plurality of latches to hold said pawls in actuated position; a plurality of releasing members for said latches, in laterally and longitudinally spaced relation with respect to each other; and means for moving said carrier longitudinally.

3. In combination, selector-bars movable along their longitudinal dimension, a pawl-carrier movable parallel to said selector-bars, associated means for moving predetermined combinations of said selector-bars by said carrier, means for yieldingly resisting movement of said selector-bars, and means for locking said resisting means in moved position.

4. In combination, selector-bars movable along their longitudinal dimension, a pawl-carrier movable parallel to said selector-bars, associated means for moving predetermined combinations of said selector-bars by said carrier, means for yieldingly resisting movement of said selector-bars, means for resisting movement of said carrier and adapted to engage said means for resisting movement of said selector-bars, and means for locking both said resisting means in moved position.

5. In combination, selector-bars movable along their longitudinal dimension, a pawl-carrier movable parallel to said selector-bars, associated means for moving predetermined combinations of said selector-bars by said carrier, means for yieldingly resisting movement of said selector-bars, means for resisting movement of said carrier and adapted to engage said means for resisting movement of said selector-bars, and means for locking both said resisting means in moved position, the resistance offered for resisting movement of said carrier being greater than that for resisting movement of said selector-bars.

6. In combination, selector-bars movable along their longitudinal dimension, a pawl-carrier movable parallel to said selector-bars, means for moving said carrier, pawls in longitudinally displaced relation to each other pivoted to said carrier and adapted to engage said selector-bars, means for causing said pawls to engage said selector-bars in predetermined combinations, latches for retaining said pawls in engagement with said selector-bars, and means for disengaging

said latches from said pawls near the end of movement of said carrier.

7. In a selecting mechanism; a plurality of movable selector bars; supporting means on which said selector bars are adapted to slide; means adapted to offer relatively light resistance to movement of said bars, a movable pawl carrier supporting a plurality of pawls and adapted to actuate said bars; means adapted to offer relatively heavy resistance to movement of said selector bars and said pawl carrier; means for selectively controlling said pawls; and means for moving said pawl carrier to cause said pawls to move said bars against said light resistance only.

8. In a selecting mechanism; a plurality of movable selector bars; means embodying a relatively light spring tending to resist motion of said selector bars; a movable carrier supporting a plurality of pawls and adapted to actuate said bars; means embodying a relatively heavy spring tending to resist motion of said bars and said carrier; means for selectively controlling said pawls; means for moving said bars against the resistance of said light spring only and for moving said carrier against the resistance of both mentioned springs; and means for causing said bars and said carrier to be restored by energy stored in both of said springs.

9. The combination as set forth in claim 8 in which the last mentioned means comprises a latch for retaining both of said springs in stressed position and means for releasing said latch to permit restoration of said bars and said carrier.

10. In a printing telegraph machine, a selecting mechanism; actuating means for said selecting mechanism; a printing mechanism controlled by said selecting mechanism; operating means for said printing mechanism; and restoring means for said selecting mechanism comprising a self locking latch mechanism set by actuation of selecting said mechanism and released by said operating means.

11. The combination as set forth in claim 10, and electrical contacts controlled by said latch mechanism.

12. In combination, printing mechanism, movable selector-bars, means for moving said selector-bars, means for restoring said selector-bars, means for locking said selector-bar-restoring means in restoring position a printing magnet, means for closing the circuit of said magnet while said selector-bar-restoring means are in restoring position, and means responsive to operation of said printing mechanism for unlocking said selector-bar-restoring means.

13. In combination, type-bars, movable selector-bars, means for moving said selector-bars, means for restoring said selector-

bars, means for locking said selector-bar-restoring means in restoring position, a printing magnet, means for closing the circuit of said magnet while said selector-bar-restoring means are in restoring position, and means responsive to operation of said type-bars for unlocking said selector-bar-restoring means.

14. In combination, printing mechanism, movable selector-bars, means for moving said selector-bars, means under constant stress for restoring said selector-bars, means for locking said selector-bar-restoring means in restoring position, and electro-magnetic means under control of said selector-bar-restoring means for operating said printing mechanism.

15. In combination, type-bars, movable selector-bars, means for moving said selector-bars, means under constant stress for restoring said selector-bars, means for locking said selector-bar-restoring means in restoring position, and electro-magnetic means under control of said selector-bar-restoring means for operating said type-bars.

16. In a printing telegraph machine, a plurality of type-bars; a plurality of selectable actuating members controlling said type-bars; a plurality of slotted selector bars; means selectively controlling said bars to align said slot in selective combinations; and an operating member directly causing a selected actuating member to enter an aligned slot and directly engaging and moving said selected actuating member across said aligned slots to effect a printing stroke of a selected type-bar.

17. The combination as set forth in claim 16 in which the operating member comprises an actuating frame supporting two universal members, one of said universal members applying the entire actuating energy necessary to effect movement of said actuating members into and out of said slots, and the other of said universal members applying the entire energy necessary to effect a printing stroke of said actuating members.

18. The combination as set forth in claim 16 in which the operating member, comprises a rigid unitary structure embodying two universal bars.

19. In a printing telegraph machine a plurality of type-bars; a plurality of selectable actuating bars controlling said type-bars; a selecting mechanism controlling said actuating bars; and a single electro-magnetic device constituting the sole agency for directly supplying and controlling all mechanical actuating energy necessary to complete operation of said actuating bars.

20. The combination as set forth in claim 19 in which the single electro-magnetic device comprises an electro-magnet.

21. In a selecting mechanism, a plurality of movable selector bars, a plurality of

- transfer and storage members adapted to actuate said selector bars, a movable carriage supporting said transfer and storage members; a plurality of electro-magnets controlling said transfer and storage members; an electro-magnet directly actuating said carriage and a locking circuit for said carriage actuating magnet opened when said carriage has been actuated.
- 10 22. In a printing telegraph machine, a selecting mechanism; a printing mechanism controlled by said selecting mechanism; operating means for said printing mechanism; a spacing mechanism; an operating magnet for said spacing mechanism; a first circuit for said spacing magnet controlled by said selecting mechanism; and a second circuit for said spacing magnet controlled by said printing mechanism; the energy 15 supplied by completion of both of said circuits being necessary to operate said spacing mechanisms.
- 20 23. The combination as set forth in claim 22 in which said first circuit embodies a high resistance and said second circuit comprises a low resistance shunt around said high resistance.
- 25 24. In a printing telegraph machine; a plurality of type-bars; a plurality of actuating bars controlling said type-bars; a selecting mechanism controlling said actuating bars; a universal operating member for said actuating bars; actuating means for said operating member; and means interposed between said operating member and said actuating means to secure uniformity of impact of successive printing blows.
- 30 25. The combination as set forth in claim 24 in which the last mentioned means comprises a spring.
- 35 26. The combination as set forth in claim 24 in which the last mentioned means spring is adjustable to vary the force of printing impact.
- 40 27. In combination, a signal, a magnet for operating said signal, type-bars, members for actuating said type-bars, shift-mechanism and means for actuating said shift-mechanism, a circuit for said magnet operatively controlled by movement of one of said members when the paper-carriage is in shifted position, and means for preventing operation of a corresponding type-bar when said member is so operated.
- 45 28. In combination, a signal, a magnet for operating said signal, type-bars, pull-bars for actuating said type-bars, shift-mechanism, means for actuating said shift-mechanism, a circuit for said magnet including a pair of contacts movable by said shift-mechanism, means actuated by one of said members and adapted to operate said contacts when the latter are in shifted position, and means for preventing operation of a corresponding type-bar when a pull-bar is operated.
- 50 29. In combination, a signal, a magnet for operating said signal, means normally short-circuiting said magnet, type-bars, pull-bars for actuating said type-bars, shift-mechanism, means for actuating said shift-mechanism, and means controlled by one of said pull-bars when the paper-carriage is in shifted position for opening a shunt about said magnet and thereby operating said signal.
- 55 30. In combination, a signal, a magnet for operating said signal, type-bars, pull-bars for actuating said type-bars, shift-mechanism, means for actuating said shift-mechanism, a circuit for said magnet including a pair of contacts movable by said shift-mechanism, means actuated by one of said pull-bars and adapted to operate said contacts when the latter are in shifted position, and means for preventing operation of the corresponding type-bar when a pull-bar is operated.
- 60 31. In combination, a paper-carriage, a ribbon-carrier, means for shifting said paper-carriage, a member actuating said ribbon-carrier in response to a printing operation, a common member actuated both by said shifting means and by said member for actuating said ribbon-carrier, and means responsive to code combinations of electrical impulses for selectively controlling operation of said combination.
- 65 32. In combination, a paper-carriage, a ribbon-carrier, means for shifting said paper-carriage, a member actuated by type-bars, a common member actuated both by said shifting means and said type-bar-actuated member for actuating said ribbon-carrier, and means responsive to code combinations of electrical impulses for selectively controlling operation of said combination.
- 70 33. In combination, a paper-carriage, a ribbon-carrier, a rocker arm on which said carrier is supported, means actuated in response to a printing operation for rocking said arm and thereby elevating said ribbon-carrier, means for shifting said ribbon carrier, means actuated by said ribbon-carrier-shifting means for bodily elevating said ribbon-carrier, and means responsive to code combinations of electrical impulses for selectively controlling operation of said combination.
- 75 34. In a printing telegraph machine; a selecting mechanism selectively controlled to incoming code combinations of electrical impulses; a printing mechanism controlled by said selecting mechanism; a ball race; a plurality of balls carried by said race; and a paper carriage pivotally and longitudinally movable on said balls and controlled by said printing mechanism.

35. In a printing telegraph machine; a selecting mechanism selectively controlled to incoming code combinations of electrical impulses; a printing mechanism controlled by 5 said selecting mechanism; a ball race, a plurality of balls carried by said race; a longitudinally and pivotally movable rack bar supported by said balls; a paper carriage mounted on said rack bar; and a stepping 10 mechanism controlling said rack bar and controlled by said printing mechanism.
36. In a printing telegraph machine the combination as set forth in claim 35 in which the stepping mechanism comprises a pinion 15 slidably engaged by said rack bar to permit pivoted and longitudinal movement of the carriage.
37. In a printing telegraph machine the combination as set forth in claim 35 in which 20 the stepping mechanism comprises an electro-magnetic actuating means controlled by said printing mechanism.
38. In a printing telegraph machine as set forth in claim 34, a guide for said balls 25 and means for moving said guide longitudinally at one half the speed of the carriage movement.
39. In a printing telegraph machine, the combination as set forth in claim 35; and a 30 clamping roll engaging said rack bar for holding said rack bar against said balls.
40. In a printing telegraph machine; a selecting mechanism selectively controlled to incoming code combinations of electrical impulses; a printing mechanism controlled by 35 said selecting mechanism; a universal member controlled by said printing mechanism; a longitudinally movable paper carriage; a rack carried by said paper carriage; a pinion 40 engaging said rack; a shaft carrying said pinion; a helical spring surrounding said shaft; and stepping means controlled by said universal bar for rotating said shaft and simultaneously storing energy in said spring 45 to restore said carriage.
41. In a printing telegraph machine, the combination as set forth in claim 40 in which the stepping means comprises an electro-magnetic actuating means controlled by 50 said universal bar.
42. In a printing telegraph machine, a selecting mechanism, a printing mechanism controlled by said selecting mechanism; a pivotally and longitudinally movable paper 55 carriage, a line feed mechanism for said paper carriage, and actuating means for said line feed mechanism controlled by said selecting mechanism; said actuating means being adapted to apply force to said line feed 60 mechanism, substantially in a line passing through the pivotal point of said carriage.
43. In a printing telegraph machine, the combination as set forth in claim 42, in which 65 the line feed actuating means comprises an electro-magnet.
44. In a printing telegraph machine, a selecting mechanism; a printing mechanism controlled by said selecting mechanism; a paper carriage embodying a platen, controlled by said selecting mechanism; a line 70 feed mechanism controlled by said selecting mechanism; a plurality of paper feed rolls co-acting with said line feed mechanism and supported on said carriage; a tension spring pressing said rolls against said platen; and 75 means to insure uniform pressure of said rolls against said platen to insure uniform line spacing by said line feed mechanism.
45. The combination as set forth in claim 44 in which the paper feed rolls are mounted 80 on bars rotatably mounted on pivoted arms and pressed against said platen; the tension spring being a spiral spring; and the means to insure uniform pressure comprising a 85 shaft on which said pivoted arms are mounted to move in opposite directions under influence of said spiral spring.
46. In a printing telegraph machine, a selecting mechanism, a printing mechanism controlled by said selecting mechanism; a 90 pivotally movable paper carriage; a shift mechanism controlled by said selecting mechanism and adapted to move said carriage pivotally; a locking mechanism to prevent pivotal movement of said carriage and released by initial movement of said shift mechanism.
47. The combination as set forth in claim 46 in which the locking means comprises a 95 lost motion connection for first releasing said carriage and then moving said carriage.
48. In a printing telegraph machine; a selecting mechanism, a printing mechanism controlled by said selecting mechanism; a ribbon feeding mechanism; actuating means 100 for said ribbon feeding mechanism controlled by said printing mechanism; and yielding connection interposed between said ribbon feeding mechanism and said actuating mechanism to avoid tearing of the ribbon.
49. The combination as set forth in claim 48 in which said yielding connection embodies a helical spring.
50. In a printing telegraph machine, a 105 plurality of type-bars; a plurality of actuating bars connected to said type-bars; a selecting mechanism controlling said actuating bars; an operating means for said actuating bars; a ribbon feed mechanism; and operating means for said ribbon feeding 110 mechanism directly actuated by said first mentioned operating means.
51. The combination as set forth in claim 50 in which the first mentioned operating means comprises a pivotally mounted frame 115 actuated by an electro-magnet; and direct mechanical connection from said frame to said ribbon-feed operating means.
52. In a printing telegraph machine; a 120 plurality of type bars; a plurality of ac- 125

tuating bars controlling said type bars; a ribbon feed mechanism coacting with said type bars; and a common bail structure for operating the selected actuating bars to directly effect the printing stroke of the selected type bar and to thereafter actuate said ribbon feed mechanism.

53. In a printing telegraph machine; a selecting mechanism; a printing mechanism controlled by said selecting mechanism; a ribbon-feed mechanism controlled by said printing mechanism; said ribbon-feed mechanism comprising a plurality of ribbon carrying spools; ratchet wheels for actuating said spools; a plurality of pawls for said ratchet wheels; and means for causing said pawls to alternately engage and be disengaged from said ratchets, comprising arms actuated by the winding and unwinding of said ribbon to control a plurality of levers controlling said pawls, whereby said ribbon feed is automatically reversed.

54. In a printing telegraph machine; a plurality of type-bars pivotally mounted on a segment of a circle; a plurality of levers pivotally mounted on a segment of a circle reversed with respect to said first mentioned segment, controlling said type-bars; a plurality of actuating bars controlling said levers and horizontally arranged; a selecting mechanism controlling said actuating bars; and an operating means for said actuating bars; said pivotal mountings being so related that the same distance of movement of said actuating bars produces a uniform distance of movement of said type-bars.

55. The combination as set forth in claim 54 in which said actuating bars are directly connected to said levers, and said levers are directly connected to said type-bars.

56. In a printing telegraph machine; a selecting mechanism; a plurality of type-bars; a plurality of actuating bars connected to said type-bars and controlled by said selecting mechanism; operating means for said actuating bars; and means controlled by said operating means to cause gradual engagement of said actuating bars with said selecting mechanism.

57. In a printing telegraph machine, a selecting mechanism, type carrying means, actuating means controlling said type carrying means, and operating means, said actuating means comprising a plurality of surfaces engaging said operating means to cause said actuating means to engage said selecting mechanism without shock.

58. In a printing telegraph machine, a selecting mechanism, type carrying means, actuating means controlling said type carrying means, and operating means, said actuating means comprising a plurality of projections and surfaces engaging said operating means to permit said actuating means to engage said selecting means gradually

and to complete a printing operation in one movement of said operating means.

59. In a printing telegraph machine a selecting mechanism, type carrying means, actuating means for said type carrying means comprising projections and surfaces; and pivotally movable operating means coacting with said actuating means to permit a selection and complete an operation of said actuating means on a forward pivotal movement of said operating means, and on a return pivotal movement of said operating means co-acting to restore said actuating means.

60. In a printing telegraph machine a selecting mechanism, a plurality of type carrying bars, selectable actuating bars connected to said type-carrying bars, inclined surfaces on said actuating bars, and a universal operating member coacting with said inclined surfaces to permit said actuating bars to move gradually into selected position and to restore said actuating bars to non-selected position.

61. In a printing telegraph machine, a selecting mechanism, a plurality of type-carrying bars selectively actuating bars connected to said type-carrying bars, each actuating bar carrying an inclined surface and an operating frame carrying a roller shaped member, said inclined surfaces and said roller shaped member coacting to gradually permit said actuating bars to move substantially without shock into selected position and restore to non-selected position.

62. In a printing telegraph machine, a selecting mechanism, a plurality of type bars, selectable actuating bars connected to said type bars, each actuating bar carrying a projection and an inclined surface, and an operating frame carrying an operating member and a universal bar, said actuating bar and said operating frame co-acting to gradually permit said actuating bars to move into selected position substantially without shock and complete an operation of a selected actuating bar in one movement of said frame, and on a return movement of said frame co-acting to restore said actuating members to nonselected position.

63. In a printing telegraph machine a selecting mechanism, a plurality of type bars, selectable actuating bars connected to said type bars, each actuating bar carrying a projection and an inclined surface, and an operating frame carrying a roller shaped member and a universal bar, said actuating bar and said operating frame co-acting to gradually permit said actuating bars to move into selected position substantially without shock and complete an operation of a selected actuating bar in one movement of said frame, and on a return movement of said frame co-acting to restore said actuating members to nonselected position.

64. In combination in a telegraph receiver, a series of type bars, a corresponding series of actuating bars for said type bars, a series of notched permutation bars for selectively controlling said actuating bars, the latter being longitudinally movable to operate said type bars and laterally movable into and out of engagement with said permutation bars; and a common unitary operating structure for effecting both the lateral and longitudinal movements of said actuating bars. 5
65. In a printing telegraph machine, selecting mechanism, a printing mechanism controlled by said selecting mechanism, an operating means for said printing mechanism, and a dash-pot for said operating means to prevent unnecessary shock to said printing means. 10
66. In a printing telegraph machine, a selecting mechanism, a movable carriage, a carriage return magnet, a pivotally mounted bar directly controlled by said selecting mechanism, and a contact member controlling said magnet and actuated solely by pivotal movement of said bar. 20
67. In a printing telegraph machine, a selecting mechanism, a movable platen, a line feeding means controlling said platen, a universal member actuating said line feeding means, an electro-magnet actuating said universal member, a pivotally mounted bar directly controlled by said selecting mechanisms, and a contact member controlling said magnet and actuated solely by pivotal movement of said bar. 30
68. In a printing telegraph machine, a selecting mechanism, a movable carriage, a spacing magnet and carriage return magnet controlling said carriage and controlled by said selecting mechanism, and means for manually releasing said carriage simultaneously from control of said magnets to permit return movement of said carriage. 40
69. In a printing telegraph machine, a selecting mechanism, a movable platen, a platen shift mechanism, a magnet actuating said shift mechanism and a locking circuit controlled by said magnet to insure sufficient energization of said magnet to completely actuate said shift mechanism. 50
70. In a printing telegraph machine, a selecting mechanism, a movable platen, a platen shift mechanism, a platen shift locking means, means under the control of said selecting mechanism for releasing said locking means, and an independent manual releasing means for said locking means. 55
71. In a printing telegraph machine, a plurality of selector bars embodying a plurality of slots and adapted to be moved in various combinations to selectively align said slots; a plurality of type bars, actuating bars for said type bars selectable by movement into said aligned slots; means responsive to code combinations of electrical impulses controlling said selector bars; means automatically operated after the reception of each code combination to effect the operation of the corresponding actuating bar and 70 means permitting a succeeding selective operation to be initiated on said first mentioned means before the actuating bar selected by the preceding selective operation has been withdrawn from the previously 75 aligned slot. 10
72. The combinations as set forth in claim 71 in which said last mentioned means comprises a transfer and storage means interposed between said first mentioned means 80 and said selector bars. 10
73. The combination as set forth in claim 71 in which said last mentioned means embodies transfer and storage means comprising a plurality of pivotally mounted actuating members for moving said selector bars, and means for selectively moving said pivotally mounted actuating members. 85
74. In a printing telegraph machine, a plurality of selector members embodying a 90 plurality of slots and adapted to be moved in various combinations to selectively align said slots; a plurality of actuating bars selectable by movement into said aligned slots; a plurality of type bars linked to said actuating bars; operating means for said actuating bars; and means for permitting a selected one of said actuating bars to move into aligned ones of said slots, before the commencement of a printing stroke of the selected type bar linked thereto, and for moving said selected actuating bar out of said aligned slots after said printing stroke has been completed. 95
75. The combination as set forth in claim 74 in which said last mentioned means comprises a universal bar. 100
76. The combination as set forth in claim 74 in which said actuating bars are moved into said aligned slots by individual springs 110 which hold the selected actuating bar in engagement with said last mentioned means during the movement of said actuating bar into and out of said aligned slots. 110
77. In a printing telegraph machine, a 115 plurality of selector members embodying a plurality of slots and adapted to be moved in various combinations to selectively align said slots; means responsive to code combinations of electrical impulses selectively 120 controlling the movement of said selector members; a plurality of actuating bars selectable by movement into said aligned slots; inclined surfaces and projecting shoulders 125 on said actuating bars; and means coacting with said inclined surfaces and said projecting shoulders to cause selected ones of said actuating bars to move into aligned ones of said slots, to cause an actuating movement of said selected actuating bar 130. 130

in said aligned slot, and to remove said selected actuating bar from said aligned slot after the actuating movement thereof has been completed.

5 78. The combination as set forth in claim 77 in which said last mentioned means comprises a movable unitary member.

10 79. In a printing telegraph machine, a plurality of selector members embodying a plurality of slots and adapted to be moved in various combinations to selectively align said slots; means responsive to code combinations of selecting conditions selectively controlling the movement of said selector members; a 15 plurality of type bars; a plurality of laterally and longitudinally movable actuating bars controlling said type bars; inclined surfaces and shoulders on said actuating bars; and a common unitary actuating structure 20 coacting with said inclined surfaces and shoulders to cause lateral movement of said actuating bars into engagement with said selector members, longitudinal movement of the selected actuating bars across said slots 25 to operate the corresponding type bars and lateral movement of said actuating bars out of engagement with said selector members.

30 80. In a printing telegraph machine a plurality of selector bars embodying a plurality of slots, electro-responsive means controlling movement of said bars to cause selective alignment of said slots in various combinations, a plurality of actuating bars selectable by movement into said slots; type 35 bars linked to certain of said actuating bars; a movable carriage mechanism comprising a rotatable platen coacting with said type-bars; and a line feed mechanism for said rotatable platen comprising a ratchet 40 wheel, a stepping pawl for said ratchet wheel, a pivoted member upon which said stepping pawl is pivotally mounted, a universal member for actuating said pivoted member, a means operated by one of said 45 actuating bars for actuating said universal member in any position of said movable carriage.

50 81. The combination as set forth in claim 80 together with means coacting with said stepping pawl to prevent an overthrow in the movement thereof.

55 82. The combination as set forth in claim 80 together with a centering detent roller, spring pressed between the teeth of said ratchet wheel.

60 83. A printing telegraph machine comprising electro-responsive means; selecting mechanism controlled by said electro-responsive means; printing mechanism controlled by said selecting mechanism a longitudinally movable carriage mechanism embodying a rotatable platen coacting with said printing mechanism and a spacing rack; a spacing drive pinion engaging said spacing rack; a ratchet wheel for driving 65

said pinion; a stepping pawl, spring pressed into engagement with said ratchet wheel; a slidable member upon which said stepping pawl is pivotally mounted, and means controlled by said selecting mechanism for reciprocating said slidable member to actuate said pawl to cause stepping of said carriage.

70 84. The combination as set forth in claim 83 in which said last mentioned means causes said slidable member to advance said pawl over the teeth of said ratchet during a printing stroke of said printing mechanism and to actuate said pawl to rotate said ratchet wheel after the printing of a character has been effected.

75 85. The combination as set forth in claim 83 together with a carriage return spring opposing the spacing movements of said carriage, and a holding pawl coacting with said ratchet wheel to prevent return of said carriage under the tension of said carriage return spring.

80 86. The combination as set forth in claim 83 together with a carriage return spring opposing the spacing movements of said carriage, a holding pawl coacting with said ratchet wheel to prevent return of said carriage under the tension of said carriage return spring, and means controlled by said 90 selective mechanism for simultaneously disengaging said stepping pawl and said holding pawl from said ratchet wheel to permit return of said carriage under influence of said carriage return spring.

95 87. The combination as set forth in claim 83 together with a carriage return spring opposing the spacing movements of said carriage, a holding pawl coacting with said ratchet wheel to prevent return of said carriage under the tension of said carriage return spring, and manually operable means for simultaneously disengaging said pawls from said ratchet wheel to permit return of said carriage under influence of said carriage return spring.

100 88. The combination as set forth in claim 83 together with a carriage return spring opposing the spacing movements of said carriage, a holding pawl coacting with said 105 ratchet wheel to prevent return of said carriage under the tension of said carriage return spring, and means for disengaging said stepping pawl and said holding pawl from said ratchet wheel until the return of said carriage is completely effected.

110 89. A printing telegraph machine comprising a selecting mechanism, a printing mechanism controlled by said selecting mechanism operating means for said printing mechanism a shift mechanism controlled by said selecting mechanism and actuated by said operating means, a shift release mechanism controlled by said selecting mechanism and actuated by said operating 115 120 125 130 132

means, and manually actuated means for operating said shift release mechanism independently of said operating means.

90. In a printing telegraph machine, type carrying means, selecting mechanism controlling said type carrying means, operating means for said type carrying means, a shift mechanism actuated by said operating means and controlled by said selecting mechanism, a spacing mechanism, a signal means operated by actuation of said type carrying means only when said shift mechanism is in actuated position, and means to prevent operation of said spacing mechanism when said type carrying means is actuated to operate said signal means.

91. In a printing telegraph machine, a selecting mechanism, a plurality of actuating members controlled by said selecting mechanism, a plurality of type-bars controlled by said actuating members, operating means for said actuating members, a shift mechanism controlled by said selecting mechanism and actuated by said operating means, a shift lock mechanism to maintain said shift mechanism in actuated position, a spacing mechanism normally operable after actuation of each type-bar, signal means operable by actuation of one of said type-bar actuating members and the type-bar connected thereto only when said shift mechanism is in actuated position, and means for preventing operation of said spacing mechanism when said signal is operated by actuation of said type-bar actuating member.

92. The combination as set forth in claim 91 in which the signal means embodies a bell, and said last mentioned means comprises a stop member for preventing completion of the printing stroke of the actuated type-bar, when the signal bell is to be operated, whereby operation spacing of the spacing mechanism is prevented.

93. In a printing telegraph receiver, a plurality of selector bars each embodying a plurality of slots and movable in various combination to selectively align said slots; means responsive to received code combinations of electrical impulses for causing selective alignment of said slots; a plurality of actuating bars selectable by movement into said aligned slots; a plurality of type bars linked to said actuating bars; and means for moving selected ones of said actuating bars into and out of said selectively aligned slots before a printing movement and after a restoring movement thereof respectively; and for moving said selected actuating bars in said aligned slots during a printing movement thereof in a manner to cause successive uniform printing impacts of selected type bars.

94. The combination as set forth in claim 93 in which said actuating means comprises a

universal actuating member common to said actuating bars.

95. The combination as set forth in claim 93 in which said operating means comprises universal operating member common to said actuating bars and a spring actuating said operating member by energy stored therein.

96. A printing telegraph machine comprising a selecting mechanism responsive to code combinations of impulses; a plurality of actuating bars controlled by said type selecting mechanism; a plurality of type bars controlled by said actuating bars; a rotatable platen coacting with said type bars; a longitudinally and vertically movable carriage supporting said platen; a line feed mechanism for said platen; and means controlled by said selecting mechanism for actuating said line feed mechanism, said means being constructed to automatically compensate for the vertical movement of said carriage.

97. The combination as set forth in claim 96 in which said means is operable to actuate said line feeding means independently of the vertical position of said carriage.

98. In a printing telegraph, a selecting mechanism, a movable platen, a platen shift mechanism, a magnet actuating shift mechanism, and a contact member controlled by said selecting mechanism and controlling said magnet.

99. In a printing telegraph machine, a selecting mechanism, a movable platen, a platen shift mechanism, a magnet adapted to actuate said shift mechanism, a contact member controlling said magnet, and a pivotally mounted bar controlled by said selecting mechanism and by a pivotal movement actuating said contact member.

100. In combination, in a printing telegraph receiver, a set of notched permutation bars, selecting means controlling the setting of said bars in response to received code combinations to selectively align the notches thereof, a series of type bars, actuating bars therefor selectable by lateral movement into the aligned slots of said permutation bars and longitudinally movable through the notches thereof to effect the operation of the corresponding type bars, and a reciprocating member for operating the selected actuating bars, said member being arranged to effect the lateral movement of said actuating bars into and out of engagement with the permutation bars at the beginning and end respectively of its forward and return movements.

101. In combination, in a printing telegraph receiver, a set of notched permutation bars, selecting means controlling the setting of said bars in response to received code combinations, to selectively align the notches thereof, a series of type bars, actuating bars therefor selectable by lateral movement into

the aligned slots of said permutation bars and longitudinally movable through the notches thereof to effect the operation of the corresponding type bars, and a common reciprocating operating member adapted upon its forward movement to successively effect the engagement of said actuating bars with said permutation bars and the operation of the selected actuating bar, and, upon its 10 turn movement, to disengage said actuating bars from said permutation bars.

102. In a printing telegraph receiver, a set of notched permutation bars, selecting means for controlling the movement of said 15 bars in response to received code combinations to selectively align the notches thereof, a series of type bars, actuating bars therefor selectable by lateral movement into the aligned slots of said permutation bars and 20 longitudinally movable through the slots to effect the operation of the corresponding type bars, and means automatically operating upon the receipt of each code combination to effect the operation of the corre-

sponding actuating bar and condition said 25 selecting means to permit the initiation of a succeeding selecting operation in advance of the completed operation of the selected actuating bar.

103. In combination in a printing telegraph receiver, a set of notched permutation members adapted to be set in different combinations to selectively align the notches thereof, printing means, a series of actuating bars selectable by lateral movement into the 30 aligned notches of said permutation members and longitudinally movable to effect the operation of said printing means, individual springs for effecting the engagement of said actuating bars with said permutation members, and a common reciprocating 35 operating member adapted by its movement to successively permit the engagement of said actuating bars with said permutation members and thereafter effect the operation 40 of the selected actuating bar.

EDWARD E. KLEINSCHMIDT.
